HARRY G. DAY AND WILLIAM E. SKINNER, OF MINNEAPOLIS, MINNESOTA

SMOKE DISPOSAL AND DRAFT INDUCING APPARATUS FOR LOCOMOTIVES

Application filed December 17, 1931. Serial No. 581,689.

This invention relates to a smoke-disposal and draft-inducing apparatus for locomotives of the type utilized in roundhouses for conducting the products of combustion from the stacks of, and for inducing draft in the furnaces of, locomotives.

The broad object of the invention is to provide an apparatus of the character mentioned which will be useful in any relation but will be more especially useful when incorporated into an ordinary or preferred form of jack as customarily employed in roundhouses, and in which will be incorporated various novel and improved features and characteristics of construction designed to render the present apparatus an improvement generally over more or less similar apparatuses heretofore known.

Further objects are to equip the up-take pipe or conduit of the apparatus with a cover actuated by improved means to be closed at all times when the apparatus is out of use and to be open at all times when a locomotive smoke stack is situated in operative position relatively to the apparatus; to equip the apparatus with a novel and improved valve adapted to close up the passage through the up-take pipe or conduit and open an exhaust passage leading from a locomotive fire box when the exhauster or blower of the apparatus is caused to function, and to open up the passage through said up-take pipe or conduit and close said exhaust passage when said exhauster or blower is not functioning; to equip the apparatus with an exhauster of novel and improved construction; to provide in the apparatus an up-take pipe or conduit of novel and improved construction; to provide in the apparatus an up-take pipe or conduit and an exhauster each of which can be associated with an ordinary or preferred type of roundhouse jack in novel and improved manner; to equip the apparatus with a raising and lowering mechanism adapted to be automatically actuated to associate the up-take pipe or conduit of the apparatus with, and to remove said up-take pipe or conduit from, the smoke stack of a locomotive in novel and improved manner; to so construct said raising and lowering mechanism

and said up-take pipe or conduit, and to so associate said mechanism and said up-take pipe or conduit with each other, that said mechanism can be actuated by the smoke stack of a locomotive to assemble said up-take pipe or conduit with, and to remove said up-take pipe or conduit from, said smoke stack; to provide in the apparatus a novel and improved arrangement permitting a locomotive smoke stack to be in communication with the up-take pipe or conduit of said apparatus at variable location in the vicinity of the apparatus, thus making it possible to move a locomotive backwardly or forwardly within limits while being fired, or while a fire exists in the fire box, without emitting smoke or gases into a roundhouse; to provide in the apparatus a novel and improved arrangement adapted to care for variations in the heights of locomotive smoke stacks; and to associate the telescoping members and barrels, respectively, of the up-take pipe or conduit of the apparatus with each other so that there can be no binding of said telescoping members and barrels.

Other objects and advantages of the invention will become apparent from the full description thereof now to be made, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is an elevational view of an apparatus in which the features of the invention are incorporated, disclosing said apparatus applied to use;

Fig. 2 is a detail sectional view taken as on line 2-2 in Fig. 4;

Fig. 3 is an enlarged vertical sectional view of the up-take pipe or conduit and the exhauster of the apparatus taken substantially as on line 3-3 in Fig. 4, with parts broken away and additionally sectioned for the sake of better disclosure; and

Fig. 4 is a vertical sectional view of the ap-

paratus taken substantially as on line 4—4 in Fig. 3.

With respect to the drawings and the numerals of reference thereon, 10 denotes the roof of a roundhouse which may have engine stalls in any desired number, 11 represents a jack above one of the engine stalls, and 12 indicates a locomotive upon a track 13 and within a stall.

10 A separate smoke disposal and draft inducing apparatus, denoted generally at 14, may be provided for each stall with jack of a roundhouse, or an apparatus made according to the invention in many of its particulars may be provided for a greater or less number of stalls which are without jacks such as 11.

Each jack 11 may be of ordinary or preferred construction. The jack disclosed is 20 shown as consisting of spaced apart, vertical side walls 15 and spaced apart, downwardly diverging end, or forward and rearward, walls 16, said side walls and end walls together providing a hollow, vertical structure having a 25 horizontally disposed, open, upper end 17 which is approximately square in configuration, and a horizontally disposed, larger, open, lower end 18 which is of rectangular shape and arranged directly above the track 30 13 with the longer sides of the rectangle extending parallel to said track.

The roundhouse roof 10 is provided with an opening 19 for each jack 11, and the jacks are arranged in said openings to approximately 35 fill the same, a major portion of the jack extending above the roundhouse roof, and a minor portion thereof projecting downwardly into the roundhouse. As disclosed, L-shaped brackets 20 attached to the roundhouse roof and to each jack, retain the jacks in stationary position.

Each side wall 15 of the jack fixedly supports a plate 21 parallel with the adjacent jack wall and slightly spaced therefrom by 45 means of bosses 22 which are desirably integral with the outer surfaces of the plates 21. The means for attaching said plates 21 to said side walls 15 of the jack consist of bolts or screws 23 which pass through the side 50 walls 15 and enter the bosses 22.

The plates 21 provide spaced apart side walls for the improved smoke-disposal and draft-inducing apparatus, and each plate 21 may be of about the configuration and size, 55 relatively to the size of the jack 11, as best disclosed in Fig. 4. That is to say, each plate 21 includes an upper rectangular portion of width slightly less than the width of a side wall 15 adjacent the upper portion thereof, 60 and a lower portion which diverges in downward direction from the lower end of said rectangular portion, the lower end of said divergent portion being of width a trifle less than the width of a side wall 15 adjacent the 65 lower portion thereof. The upper end of

each plate 21 may desirably terminate a trifle above the upper end of the jack 11, while the lower end of each said plate 21 may terminate at considerable distance above the lower end of said jack, as said plates are shown in Figs. 70 3 and 4. The upper and lower edges, respectively, of the plates or side walls 21 desirably terminate in the same horizontal plane.

Upper end, or upper forward and rearward, walls of the up-take pipe or conduit 75 of the apparatus are designated 24, said end walls 24 being disposed vertically and being arranged in spaced apart, parallel relation to each other. The walls 24 are rigidly secured to and between the plates or side walls 21 of the apparatus in any convenient manner to provide a rectilinear box constituting the upper portion of said up-take pipe or conduit and including all of the walls 24, 24 and parts of the walls 21, 21.

The up-take pipe or conduit of the apparatus also includes an upper intermediate portion or passage constituted by lower portions of the plates or side walls 21 and by downwardly extending, swingable members 25 90 which are hingedly supported upon the lower ends of the end walls 24, as at 26, said members 25 each being of width to extend practically the full distance between said plates or side walls 21, as shown more clearly in Figs. 3 and 4, so that the passage provided by said plates or side walls 21 and said members 25 will be, in effect, swingable transversely of the structure constituting the up-take pipe or conduit of the apparatus. Each of the members 25 consists of telescoping plates 27 adapted to have movement toward and from each other whereby to accomplish longitudinal adjustment of each said member 25. As shown, one of the plates 27 of each member 25 supports spaced apart headed and nutted bolts 28, including a headed and nutted bolt arranged in each of parallel slots 29 in the other plate 27 of said member 25, and a small cover plate 30 is arranged over each slot 29 to render said members 25 smoke-tight.

The members 25 slant toward one side of the jack 11 and converge in a downwardly direction, in the manner as best disclosed in Fig. 4. A barrel 31, constituting a lower intermediate portion of the up-take pipe or conduit of the apparatus, has the forward and rearward side edges of its upper portion hingedly supported, as at 32, upon the lower edges of the lower plates 27 of both members 25. The upper portion of the barrel 31 is oblong in cross-section, including longer walls 33 adjacent the hinges 32 and extending between the plates or side walls 21 at the location of the upper parts of said walls 33, and shorter walls 34 having their upper edges arranged to slide over said plates or side walls 21. The walls 33 and 34 which provide said upper portion of the barrel 31 extend downwardly beyond the plates or side 125 130

walls 21 and merge at their lower extremities into a cylindrical part 35 which constitutes the lower portion of said barrel 31. Said cylindrical part 35 of the barrel 31 is situated between spaced apart, parallel runways 36 arranged in a plane which is parallel to the plane of the track 13, directly above said track. Also, said runways 36 extend in the direction of the length of said track 13, and have their opposite ends rigidly supported upon the end, or forward and rearward, walls 16 of the jack, as denoted at 37 in Fig. 3. The cylindrical part 35 of said barrel 31 integrally supports bosses, denoted 38, including four bosses 38 extending outwardly of said cylindrical part from each side thereof, all of the bosses at a side of the cylindrical part being parallel with each other and perpendicular to the runway 36 at the corresponding side of the barrel. The four bosses 38 at each side of the cylindrical part 35 of the barrel 31 are arranged in two sets of bosses with two bosses to the set, one set of bosses 38 being a trifle above the corresponding runway 36, and the other set of bosses being a trifle below said corresponding runway. All of the bosses 38 of the two upper sets of bosses, at both sides of the cylindrical part 35, are in the same horizontal plane, as are also all of the bosses 38 of the two lower sets, at both sides of said cylindrical part. A roller 39 is mounted in each boss 38 and each roller 39 is flanged, as at 40, to fit upon an edge of a runway 36, it being apparent that the cylindrical part 35 of the barrel 31 is thus fixed to the runways 36 to be slidable therealong, there being four upper rollers 39 rigidly supported by and spaced about the cylindrical part 35 with opposite rollers resting upon the upper edges of the different runways, and four lower rollers 39 also rigidly supported by and spaced about said cylindrical part with opposite rollers in contiguous relation with, or closely adjacent to, the lower edges of the different runways, and there also being a lower roller 39 directly opposite and beneath each upper roller 39.

A lower barrel 41 of the up-take pipe or conduit of the apparatus has its upper end portion telescopically received in the lower or cylindrical part 35 of the barrel 31, and the flanged upper end 42 of the barrel 41 lies in the oblong portion of said barrel 31 to limit the extent of downward movement of said barrel 41, as will be more clear from Fig. 3. The pivotal arrangement at the hinges 26 and 32 is such that the barrel 31 can have movement lengthwise of the runways 36 in either direction, the members 25 lengthening or shortening, as the case may be, depending upon the direction in which said barrel 31 is slid along said runways. That is to say, when the barrel 31 is slid along the runways 36 from its position as in Fig. 4 toward the left, the members 25 will shorten as said barrel 31 moves, naturally, closer to the hinges 26, and when said barrel 31 is slid along the runways in opposite direction, said members 25 will lengthen as the barrel moves farther from said hinges 26, the shortening and lengthening operations of said members 25 being permitted by the slot and bolt connections of the plates 27, as hereinbefore set forth. As will be apparent, the members 25 are mounted to be swingable longitudinally of the track 13, and the barrel 31 is mounted to be reciprocable longitudinally of said track. As will hereinafter become apparent, the barrel 41 is adapted to have vertical movement in the barrel 31, said barrel 31 desirably being vertically disposed. Said barrel 41 extends to position somewhat beneath the jack.

A raising and lowering mechanism of the apparatus, represented generally at 43, is adapted to be actuated by the smoke stack of a locomotive to associate the lower barrel 41 with said smoke stack and to remove said lower barrel from said smoke stack. Of said raising and lowering mechanism, 44 designates spaced apart suspension slabs (only one being shown) upon the roundhouse structure suitably supporting upper and lower, horizontal cross shafts, indicated 45 and 46, respectively, and 47 denotes a raising and lowering bar extending substantially longitudinally of the track 13, the rearward end portion of said bar 47 being freely received between said suspension slabs and said horizontal cross shafts in such manner that the bar can have upward and downward swinging movement, as well as longitudinal sliding movement, but can have very little lateral or sidewise movement. The forward end portion of the bar 47 is pivotally attached, as at 48, to a barrel carrier 49, which carrier is in turn rigidly attached, in any suitable manner as by welding or otherwise, to the lower barrel 41. The pivotal arrangement between the bar 47 and the barrel carrier 49 is such that said bar and carrier can have vertical swinging movement relatively to each other. The lower portion of the barrel 41 is of configuration best suited to the reception of a locomotive smoke stack which is adapted to positively enter the flared mouth 50 of said lower barrel, and said mouth 50 is cut away at one of its sides, as shown at 51, adjacent the bar 47, to allow entry of a smoke stack into said mouth 50. Also, the cut-away portion 51 of the mouth 50 is desirably at slightly higher elevation than the lower surface of the adjacent end portion of the bar 47 to better insure ready travel of a smoke stack along said bar 47 and into said mouth 50, in the manner presently to be set forth.

A counterweight 52, suspended from a cord 53 which rides over fixed pulleys 54 and is attached to the bar 47 as at 55, is for the

purposes of counter-balancing said bar 47 and of normally situating said bar and the barrels 31 and 41 at the dotted line position disclosed in Fig. 1, which corresponds to the position of the parts of the apparatus as in Fig. 4.

A cover 56 for the upper end of the up-take pipe or conduit, constituted by the walls 21, 21, 24, 24, is adapted to be closed at all times when the apparatus is out of use and is adapted to be open at all times when a locomotive smoke stack is situated in operative position relatively to the apparatus. As disclosed, the cover 56 is pivoted upon an upper portion of one of the plates or side walls 21, as at 57, and includes a protruding arm 58 carrying a weight 59 of sufficient magnitude to move said cover to open position. A cord or wire 60 attached to the cover 56 at the side 10 of its pivot opposite the weight 59 is also attached, at its opposite end, as at 61, to a shaped element 62 itself welded or otherwise connected to the flared mouth of the lower barrel 41. As disclosed more clearly in Figs. 15 25 and 4, the cord or wire 60 passes downwardly between the plate or side wall 21 having the pivot 57 and the adjacent side wall 15 of the jack, and rides over an idler pulley 63 which is suitably mounted upon this same 30 mentioned plate or side wall 21, desirably at about the location as shown. The arrangement is such that when the barrel 41 is moved to its lowermost position by its own weight and the weight of the bar 47, the cord or wire 35 40 50 55 60 65 70 75 80 85 90 95 100 105 110 115 conduit. Obviously, when the fan 64 is brought to rest, the weight 74 immediately acts in the manner as hereinbefore set forth to move said valve 71 to its full line position as in Fig. 3, thus closing said exhaust passage and opening the up-take pipe or conduit.

Supposing the bar 47 to be in normal position, say, for example, as disclosed in dotted lines in Fig. 1, and it is desired to associate a locomotive smoke stack with the mouth 50 of the lower barrel 41 of the up-take pipe or conduit, all that is necessary to be done to accomplish this result is to move the locomotive from the dotted line position of the smoke stack in said Fig. 1 toward the full line position of the locomotive disclosed, until said smoke stack has caused the bar 47, together with the lower barrel 41, to be elevated, and 20 has entered said mouth 50 of said lower barrel. The arrangement is such that the smoke stack will snugly fit into the mouth 50 when at any one of several different positions, as the barrel 31 slides longitudinally of the runways 36, to provide a smoke-tight association between said stack and the up-take pipe or conduit, as will be understood. After the smoke stack has associated itself with the mouth of the lower barrel 41, movement of 30 said smoke stack still farther ahead will obviously cause said lower barrel and the bar 47 to be still farther elevated and said bar 47 to be slid longitudinally ahead. Upon return movement of the locomotive, the smoke stack 35 will not be removed from the up-take pipe or conduit until the rearward position at which the smoke stack entered the mouth 50 has been passed, so that a locomotive can be moved forwardly and backwardly within limits 40 while associated with the up-take pipe or conduit of the apparatus without permitting smoke or gases to be emitted into a round-house.

The utilization of the improved raising and lowering mechanism actuated by the smoke stack of a locomotive to associate the up-take pipe or conduit with, and to disassociate said up-take pipe or conduit from, said smoke stack, eliminates all labor and maintenance which have heretofore been required to accomplish the association and disassociation of stacks with apparatuses of the present character, and the arrangement as disclosed 55 obviously makes provision for variations in the heights of locomotive smoke stacks.

As will be evident, whenever the bar 47 and the lower barrel 41 are elevated by a smoke stack, the cover 56 will be in open position, and when said bar and barrel are allowed to lower, said cover will be closed.

Particular attention is called to the fact that the only time the valve 71 of the apparatus is positioned as in dotted lines in Fig. 3, 60 is when the fan 64 is exhausting. At all other

times, said valve 71 is positioned as shown in full lines in said Fig. 3.

What we claim is:

1. In an apparatus of the character described, an up-take conduit including a longitudinally slideable and vertically movable lower member adapted to be associated with the smoke stack of a locomotive, and means adapted to be actuated responsively to the approach of a locomotive for assembling said lower member and said smoke stack with each other. 70

2. In an apparatus of the character described, an up-take conduit including a longitudinally slideable and vertically movable lower pipe adapted to be associated with the smoke stack of a locomotive, and means adapted to be actuated responsively to the approach of a locomotive for causing said smoke stack to enter the mouth of said lower pipe. 80

3. In an apparatus of the character described, an up-take conduit including a lower member mounted to be longitudinally slideable in the direction of travel of a locomotive and vertically movable, and means adapted to be actuated responsively to the approach of a locomotive for associating said lower member with the smoke stack of said locomotive. 90

4. In an apparatus of the character described, an up-take conduit including a longitudinally slideable and vertically movable lower member adapted to be associated with the smoke stack of a locomotive, and means adapted to be actuated responsively to the approach of a locomotive for associating said lower member and said smoke stack with each other, said smoke stack being adapted to be automatically disassociated from said lower member whenever said locomotive departs from the general vicinity of said lower member. 95

5. In an apparatus of the character described, an up-take conduit mounted above rails adapted to carry a locomotive, said up-take conduit including a lower member mounted to be slideable longitudinally of said rails and to have a raising and a lowering movement, and means responsive to the approach of a locomotive to situate said lower member at position to be entered by the smoke stack of said locomotive. 100

6. In an apparatus of the character described, an up-take conduit including a lower pipe adapted to be associated with the smoke stack of a locomotive, said lower pipe being mounted to slide relatively to a smoke stack and to be capable of having a raising and a lowering movement, and means responsive to the approach of a locomotive to situate said lower pipe at position to be entered by the smoke stack of said locomotive. 115

7. In an apparatus of the character described, an up-take conduit including a longitudinally slideable and vertically movable 120

lower member adapted to be associated with the smoke stack of a locomotive, means adapted to be actuated responsively to the approach of a locomotive to situate said lower member at position to be entered by said smoke stack, a cover for said up-take conduit, means for normally maintaining said cover in closed position, and means for maintaining said cover in open position when said lower member is in position to be entered by said smoke stack.

8. In an apparatus of the character described, an up-take conduit comprising a plurality of pipes arranged to have movement relatively to each other, including a lower pipe adapted to be associated with the smoke stack of a locomotive, and an upper pipe with which said lower pipe communicates to carry products of combustion away from said smoke stack, said lower pipe being mounted to be slidable longitudinally of a track carrying said locomotive and to have vertical movement, means adapted to be actuated responsively to the approach of a locomotive to situate said lower pipe at position to be entered by said smoke stack, a cover for said upper pipe, means connecting said cover with said lower pipe for normally maintaining the cover in closed position, and means for maintaining said cover in open position when said lower pipe is in position to be entered by said smoke stack.

9. In an apparatus of the character described, an up-take conduit mounted above rails adapted to carry a locomotive, said up-take conduit including a lower pipe mounted to be slidable longitudinally of said rails and to have a raising and a lowering movement, and means attached to said lower pipe and responsive to the approach of a locomotive to situate the mouth of said lower pipe at position to be entered by the smoke stack of said locomotive, said lower pipe being adapted to have upward and downward vertical movement and sliding movement in the direction of travel of said smoke stack while said smoke stack is associated with said lower pipe.

10. In an apparatus of the character described, an up-take conduit comprising a plurality of pipes arranged to have movement relatively to each other, including a longitudinally slidable and vertically movable pipe adapted to be associated with the smoke stack of a locomotive and a pipe with which the first mentioned pipe communicates to carry products of combustion away from said smoke stack, a cover for the upper end of said second pipe mounted exteriorly thereof, means normally maintaining said cover in closed position, and means actuated by relative movement between said pipes for actuating said cover to open position.

11. In an apparatus of the character described, an up-take conduit comprising a plurality of members, including an upper mem-

ber, an intermediate member pivoted upon said upper member, and a lower member adapted to be associated with the smoke stack of a locomotive, said lower member being mounted to be slidable in the direction of movement of said locomotive and vertically movable and having a portion normally situated below the elevation of the upper portion of said smoke stack, a cover for said upper member, means connecting said cover with said lower member for normally maintaining the cover in closed position, and means for maintaining said cover in open position when said lower member is elevated to be associated with a locomotive smoke stack.

12. In an apparatus of the character described, an up-take conduit comprising a plurality of pipes, including an upper pipe, an intermediate member pivoted upon said upper pipe, and a lower pipe adapted to be associated with the smoke stack of a locomotive, said lower pipe being mounted to be longitudinally slidable and vertically movable and having a portion normally situated below the elevation of the upper portion of said smoke stack, means limiting downward movement of said lower pipe, a member connected to said lower pipe and adapted to be elevated by said smoke stack to situate said lower pipe at position to be entered by the smoke stack, a cover for said upper pipe, means connecting said cover with said lower pipe for normally maintaining said cover in closed position, and means for maintaining said cover in open position when the smoke stack elevates said member.

13. In an apparatus of the character described, an up-take conduit comprising a plurality of pipes arranged to have movement relatively to each other, including a lower pipe adapted to be associated with the smoke stack of a locomotive and an upper pipe with which said lower pipe communicates to carry products of combustion away from said smoke stack, a portion of said lower pipe being normally situated below the elevation of the upper portion of said smoke stack, and a member mounted for swinging and longitudinal movement and connected to said lower pipe and adapted to be elevated by said smoke stack to situate the mouth of said lower pipe at position to be entered by the smoke stack, said lower pipe being mounted to be slidable longitudinally relatively to said member and to have a raising and a lowering movement.

14. In an apparatus of the character described, an up-take conduit comprising a plurality of members arranged to have movement relatively to each other, including a lower member adapted to be associated with the smoke stack of a locomotive and an upper member with which said lower member communicates to carry products of combustion away from said smoke stack, a portion of said

lower member being normally situated below the elevation of the upper portion of said smoke stack, means limiting downward movement of said lower member, and a member

5 mounted for vertical swinging and longitudinal movement and pivotally connected to said lower member and adapted to be elevated by said smoke stack to situate said lower member at position to be entered by the smoke stack,
10 said lower member being mounted to be slideable longitudinally of said member and to have a raising and a lowering movement.

15. In an apparatus of the character described, an up-take conduit having side walls
15 adapted to be attached to the side walls of a roundhouse jack, said up-take conduit including an upper pipe constituted by portions of said side walls and transverse members between said portions of the side walls, an upper intermediate pipe pivotally supported upon said upper pipe, said upper intermediate pipe being constituted by portions of said side walls and by spaced apart, telescoping members between said portions of the side walls, a lower intermediate pipe pivotally supported upon said transverse members, a lower pipe adapted to be associated with the smoke stack of a locomotive,
25 said lower pipe being arranged in sliding relation to said lower intermediate pipe and having a portion normally situated below the elevation of the upper portion of said smoke stack, a runway for said lower intermediate pipe having its length arranged in the direction of travel of the smoke stack, means for attaching said lower intermediate pipe to said runway in such manner that said lower intermediate pipe can have longitudinal movement along said runway, means limiting downward movement of said lower pipe, and a member connected to said lower pipe, said member being mounted to slide in the direction of movement of the smoke stack and being adapted to be elevated to situate said lower pipe at position to be entered by a locomotive smoke stack.

16. In an apparatus of the character described, an up-take conduit including a member having fixed side walls and vertically swingable, longitudinally adjustable end walls, a pipe pivotally supported by said longitudinally adjustable end walls and extending downwardly therefrom, and a lower pipe
50 telescopically received in the first mentioned pipe to have a raising and a lowering movement therein, said lower pipe being adapted to be associated with the smoke stack of a locomotive, means limiting downward movement of said lower pipe, a member connected to said lower pipe and mounted to slide in the direction of movement of the smoke stack, said member being adapted to be elevated by said smoke stack to situate said lower pipe
55 at position to be entered by the smoke stack,

a runway extending in the direction of travel of said smoke stack, and means attaching said first mentioned pipe to said runway for sliding movement only relatively thereto.

17. In an apparatus of the character described, an up-take conduit including an upstanding pipe, a lower upstanding pipe telescopically received in the first mentioned pipe and adapted to be associated with the smoke stack of a locomotive, a member connected to said lower pipe, said member being mounted to have movement in the direction of movement of the smoke stack and being adapted to be elevated by the smoke stack to situate said lower pipe at position to be entered by said smoke stack, a runway for the first mentioned pipe, and means for attaching said first mentioned pipe to said runway in such manner that said pipe can have sliding movement along said runway in the direction of travel of said smoke stack.

18. In an apparatus of the character described, an up-take conduit including an up-take pipe adapted to be associated with the smoke stack of a locomotive, a member connected to said up-take pipe and mounted to have movement in the direction of travel of the smoke stack and adapted to be elevated responsively to the approach of a locomotive to situate said up-take pipe at position to be associated with said smoke stack, means supporting said up-take pipe for sliding movement in the direction of travel of said smoke stack, and means permitting said up-take pipe to have a raising and a lowering movement.

19. In an apparatus of the character described, an up-take conduit adapted to lead from a locomotive fire box, an exhauster with which said up-take conduit is adapted to communicate, there being an inlet to said exhauster from a portion of said up-take conduit and an outlet from said exhauster to a different portion of said up-take conduit, and a valve mounted within said up-take conduit at location between said exhauster inlet and said exhauster outlet, said valve being adapted to shut off passage through the up-take conduit and to open an exhaust passage leading from said locomotive fire box when said exhauster is operating, and to open passage through said up-take conduit and close said exhaust passage when the operation of said exhauster is stopped.

20. In an apparatus of the character described, an up-take conduit adapted to lead from a locomotive fire box, an exhauster outside of said up-take conduit, there being an inlet to said exhauster from a portion of said up-take conduit and an outlet from said exhauster to a different portion of said up-take conduit, a valve mounted within said up-take conduit at location between said exhauster inlet and said exhauster outlet, and means for maintaining said valve in position to close

said exhauster outlet and to open passage through said up-take conduit when said exhauster is inoperative, said valve being responsive to actuation of said exhauster to shut off passage through the up-take conduit and to open an exhaust passage from said locomotive fire box and including said exhauster inlet and said exhauster outlet.
